[57] CLAIM

The ornamental design of a snow removal tool, substantially as shown.

DESCRIPTION

FIG. 1 is a perspective view of a snow removal tool showing our new design;

FIG. 2 is a front elevational view thereof at an enlarged scale;

FIG. 3 is a side elevational view as seen from the right-hand side of FIG. 2;

FIG. 4 is a rear elevational view thereof;

FIG. 5 is a top plan view thereof; and

FIG. 6, is a bottom plan view thereof.
